AIR-OIL PUMP

Eric Colin-Smith, Wellesley, Mass., assignor to Combustion Research Corporation, West Newton, Mass.
Continuation of application Ser. No. 91,953, Feb. 27, 1961. This application Dec. 20, 1963, Ser. No. 333,790
2 Claims. (Cl. 103—9)

This is a continuation of application Serial No. 91,953, filed February 27, 1961, now abandoned.

This invention relates to a combined air and oil pump device particularly for use in oil burner installations wherein air and oil are required to be delivered at a regulated volume flow and pressure to an atomizing nozzle for controlled combustion characteristics. It will be understood, however, that the device will have many other applications, for instance, in the agricultural spraying field.

The principal object of the invention is to provide a highly efficient air-oil pump of simple and inexpensive construction which will enable the air and oil volumes and pressures delivered by the pump to be quickly and easily adjusted to suit the requirements of the particular installation with which it is used.

A further important object is to provide such an air-oil pump which can be utilized to replace existing oil pumps on the conventional gun type burners to enable the ready conversion of such burners from installations relying solely on draft tube secondary air for combustion to relatively more efficient installations utilizing pressure primary air for oil atomization according to the said co-pending application.

Still another important object is to enable the air-oil pump to be driven either directly or through a suitable coupling either from its own motor or from the existing driving motor of the conventional oil burner installation, and more particularly to enable the air-oil pump to operate efficiently irrespective of the direction of rotation of the driving motor so that the one pump unit will have universal application to make for very simple field installations.

The principal feature of the invention resides in providing a main body housing separate rotary air and oil pumps driven from a common drive, and providing a flow controlling and metering valve unit associated with each pump section whereby volume and pressure of flow delivered by each pump is easily and quickly controlled without altering pump action.

Another and important feature resides in so constructing the pumps that they will function equally efficiently when rotated in either direction so that the inlet and outlet connections can be interchanged at will whereby the device can be connected to drive motors irrespective of their direction of rotation.

In this connection, still another feature resides in forming the air-oil pump device with mounting means for convenient mounting in conjunction with conventional gun type burners to utilize the existing driving motor of such burners as the drive therefor.

Further, in this connection, another important feature resides in forming the flow controlling valving units as separate demountable and reversible units whereby connections to the pumps can be readily achieved to accommodate reversal of pump rotation, thereby rendering the entire system completely universal so that it can be easily and quickly installed in the field regardless of the direction of motor drive encountered, thus allowing standardization of the system, simplifying production and reducing stocking of component parts.

Still another feature resides in providing the flow controlling units with very precise and easily operated flow volume and pressure setting controls for adjustment of air and oil feed in the field.

2

Other features reside in the details of construction and arrangement of the air-oil pump device, and these and other features and objects will become apparent from the following detailed description taken in conjunction with the accompanying drawings in which:

FIGURE 1 is a perspective view partly broken away of an oil burner installation employing an air-oil pump embodying my invention;

FIGURE 2 is an exploded perspective view of the air-oil pump device shown in FIGURE 1;

FIGURE 3 is a longitudinal mid-vertical sectional view taken through the pumping section of the device;

FIGURES 4 and 5 are transverse, vertical, sectional views taken on the lines 4—4 and 5—5 of FIGURE 3;

FIGURE 6 is a horizontal, sectional view taken through the air flow control unit; and

FIGURE 7 is a fragmentary, vertical, sectional view showing the oil feed through the bleed passage arrangement from the oil reservoir in the oil flow control unit up to the air pump rotor.

With reference to FIGURE 1, the air-oil pump, according to the present invention, is shown, generally designated at 1 being mounted in conjunction with a conventional type motor and blower unit 2 of a gun-type domestic burner, the unit being carried on a suitable standard 3 supported by a mounting base 4. The drive to the air-oil pump device 1 is achieved from the motor of the motor and blower unit 2 as hereinafter more fully described, and the device 1, including an air flow control unit generally designated at 5 and an oil flow control unit generally designated at 6, is arranged to deliver air and oil at the requisite pressures and at the required volume flow through air and oil lines 7 and 8 to feed a burner head 9, preferably of the type disclosed in my co-pending application, Serial No. 91,953, mounted in a draft tube 10 projecting into a combustion chamber 11.

With reference to FIGURE 2, it will be seen that the air-oil pump device 1 is separable from the air flow and oil flow controlling units 5 and 6, and reference is to be had to FIGURES 3 to 5 for details of the air pumping section of the device generally designated at 12 and the oil pumping section of the device generally designated at 13.

The air pumping section 12 comprises a generally cylindrical casing 14 having a cylindrical chamber 15 formed therein. Leading from the chamber 15 through a downwardly projecting portion 16 of the casing 14 are spaced passageways 17 and 18. Eccentrically mounted within the chamber 15 is a rotor 19 carrying radially slidable vanes 20, the rotor being mounted on a shaft 21 supported in end bearing blocks 22 and 23 bolted or otherwise secured to the opposite end of the cylindrical casing 14. Mounted in suitable counterbores in the end blocks 22 and 23 are suitable bearings 24 through which the shaft 21 extends. The shaft extends through an end seal 25 and a gland nut 26 beyond the end of the left bearing block 22 for connection to a driving motor such as the motor of the motor blower unit 2 in FIGURE 1, the shaft end being arranged for direct connection or for connection through any suitable coupling as will be understood.

Secured to the outward end of the right hand bearing block 23 is an oil pump casing 27 having a cylindrical chamber 28 formed therein. Communicating with the chamber 28 are passageways 29 and 30 having enlarged internally threaded entrances 29' and 30'.

The shaft 21 has a reduced extension 31 which projects through a suitable end seal 32 into the chamber 28 with the axis of the reduced extension 31 being eccentric to the axis of the chamber.

Mounted on the reduced shaft extension 31 is an oil pumping rotor 33 secured to the shaft by means of a

key 34, the rotor carrying a series of radially slideable vanes 35.

The outer face of the oil pump casing 27 is closed by a block 36 having a reduced portion extending into the chamber 28 and a cap 37, suitable gaskets 38 and 39 being provided to effect a complete seal, and further gasket 40 being provided between the casing 27 and the right hand end bearing block 23.

Secured to the downwardly projecting portion 16 of the air pump casing 14 is a mounting face or base plate 41 having formed therein registering ports 17' and 18' adapted to register with the passageways 17 and 18. A suitable gasket 42 is interposed between the plate 41 and the casing base 16.

Leading up through the base plate 41 centrally thereof and up through the downward extending portion 16 of the air pump section casing 14 is a passageway 43 which terminates in a small orifice 44 opening into the air pumping chamber 15. Leading laterally from the passageway 43 are feed passages 45 which are arranged to intersect with passages 46 in the end bearing blocks 22 and 23, these passages containing wicks 47 leading to the bearings 24 whereby oil delivered under pressure as hereinafter more fully explained through the passage 43 will feed into the air chamber 15 to provide an oil seal between the passages 17 and 18 and will feed laterally to the wicks 47 to be delivered to the bearings 24 for lubrication.

With the pumps illustrated, it will be understood that a pumping action will be achieved regardless of which direction of rotation is imparted to the pumping rotors 19 and 33. With the direction of rotation counterclockwise, as shown in FIGURE 4, the vanes 20 of the air pump will suck air in through the passageways 18 which thus form the intake passages and will discharge compressed air through the passages 17 which thus form the discharge passages. It will be understood, of course, that the reverse rotation of the rotor will reverse the function of the passages 17 and 18 as intake and discharge passages.

Viewing FIGURE 5, it will be apparent that with the counterclockwise rotation oil will be sucked into the pumping chamber 28 through the passageway 30 which will then form the intake passage and will be delivered out through the passage 29 which will then form the discharge passage. Upon reversal of rotor rotation, of course, the function of the passages will be reversed. The manner in which the air and oil flow is controlled is an important aspect of the invention, and with reference particularly to FIGURES 2 and 6, it will be seen that the discharge ports 17' and 18' formed in the base plate 41 are symmetrical with respect to each other and with respect to the base plate and with the central passage 43. This relationship of the ports is important with respect to the simplification of the ease with which pump can be reversed through the simple rotation of the air flow control unit or block 5 from end to end; that is, rotation through 180° in its own plane as hereinafter more fully explained. Assuming that the direction of rotation is such that the ports 18' form the intake ports and the ports 17' form the discharge ports from the air pumping section, the air flow control unit 5 is arranged as illustrated in FIGURE 2 and FIGURE 6. In this connection it will be seen that this unit comprises a block having an intake passage 48 leading in from one end to a cross passage 49 plugged at opposite ends with the cross passage opening through ports 50 which are adapted to register with the ports 18' in the mounting base when these latter ports are forming the intake ports for the air pump section.

Preferably an air silencer generally designated at 51, as particularly seen in FIGURE 6, is threaded into the entrance to the intake passage 48 to provide for low level sound of operation of the air pump, the device comprising a cylinder housing a series of baffles 52 and 53 providing for a tortuous air flow path.

The air flow control block 5 is provided with a further cross passage 54 parallel the passage 49 again plugged at the ends, and this passage communicates through ports 55 in the upper face of the block corresponding to the ports 50. These ports are adapted to register with the ports 17' in the base plate 41 when the latter ports form discharge ports for the air pumping section.

Thus it will be seen that the ports 50 and 55 are symmetrical with respect to each other and with respect to the air control unit or block 5 and also with respect to a central orifice 56 through the block 5 so that should the direction of the air pump rotation be reversed, a simple end-to-end shifting of the block 5 will maintain the intake ports 50 in registering communication with the intake ports of the air pump section now the ports 17' and vice versa. Leading from the cross passage 54, is a threaded bore 57 opening into an enlarged bore 58 opening through the end of the block. Mounted in the bores 57 and 58 is a valve device generally designated at 59 which has a reduced hollow inner end 60 threaded into the threaded bore 57 and an enlarged internally threaded sleeve portion 61 having discharge ports 62 communicating to a peripheral groove 63 in the perimeter thereof. The valve is provided with a shoulder 64 and suitable O-rings 65, one encircling the threaded portion 60 and the other the sleeve portion 61 beneath the shoulder 64, provide for fluid seals. Threadably mounted in the sleeve portion 61 is a spindle 66 carrying a needle or pin projection 67 extending into the reduced sleeve portion 61. Outwardly of the needle portion 67, the spindle is provided with a bevelled shoulder 68 arranged to seat on a bevelled valve seat 69 to block fluid flow through the bore 57. The needle 67 is provided with a V-groove formation 70 therein which permits an increasing volume flow as the spindle 66 is backed off to raise the shoulder 68 from the valve seat 69. It has been found that this V-groove gives a very precise volume flow control under spindle movement. The spindle 66 projects through a cap or gland 71 and is provided with a suitable control wheel 72. Leading laterally from the bore 58 is a discharge port 73 which receives an air flow pipe which constitutes the air line 7 for delivering air to the burner head or other installation.

In addition to the flow path through the valve-controlled passage leading to the discharge port 73 is a further flow path leading to an air exhaust port 74 communicating with the atmosphere through an air silencer 51. This latter flow path is afforded through the provision of a bore 75 parallel to the bore 58 and terminating in a reduced threaded bore 76 opening into the cross passage 54. A pressure control valve generally designated at 77 is mounted in the bores 75 and 76, the valve comprising a hollow body 78 having a reduced threaded portion 79 threading into the bore 76 with the body opening into the cross passage 54. The body is provided with a shoulder 80 and suitable O-rings or gaskets 81 are used to effect seals against air leakage externally of the body. Formed within the body 78 is a valve seat 82 with which co-operates a ball valve 83 held by a cup 84 carried on a stem 85 slidably received and guidably supported in a threaded sleeve 86 which threadably engages an internal threading 87 of the body, the sleeve 86 being provided with a slot 86' in its end for screw driver engagement. A cap 88 encloses the sleeve 86 in the body 78.

Sleeved on the stem 85 is a spring 89 which is received in a counterbore 90 in the sleeve 86 and this spring acts on the cup 84 to urge the ball to seat against its valve seat 82. By adjusting the sleeve 86 axially of the body 78, the spring tension and hence pressure at which the ball will lift from its valve seat to allow air flow therewith can be precisely and accurately set.

The body 78 has ports 91 therein communicating with an external groove 92 to allow air passing ball valve 83 to escape to the air exhaust port.

Thus, by setting the valves 59 and 77, the requisite air flow through the air line 7 can be accurately predeter-

mined as to volume and pressure, and if the direction of the air pump rotation is reversed to reverse the direction of air flow, the block 5 can be quickly and easily reversed by turning end to end to accommodate such pump reversal.

FIGURE 2 shows the details of the oil flow control unit and assuming oil is entering the oil pump section 13 through the infeed line 93, then oil will be discharged from this section through the discharge oil line 94. The line 94 leading from the oil pump unit connects through an intake port 95 provided in the oil flow control unit 6, which is in the form of a block of corresponding size to the block 5, and this intake port 95 communicates with a central oil well 96 from which leads a passageway 97, flow control through which is controlled by a valve 59', corresponding ponding to the valve 59 described in connection with the air flow control unit, and discharging from the valve-controlled passageway 95 is a discharge port 98 connected through an oil line comprised by the oil line 8 referred to in FIGURE 1.

Also in communication with the well 96 is a passageway 99 controlled by a pressure control valve 77', corresponding to the pressure control valve 77, and leading from this valve-controlled passageway 99 is a by-pass 100 communicating through oil line 101 to the intake side of the oil pump section.

Projecting up through the oil well 96 is a body member 103, FIGURE 7, threaded into a boss 104 at the bottom of the block 6. A cylinder 105 having a reduced lower end received in the body member 103 and a reduced threaded upper end threaded into a counterbore formed in the underside of the block 5 is provided internally with a needle valve seat 106 and feed passages 107 and a fine bore 108 leading through the upper end to communicate with the central passages 56 and 43 formed through the air control block and the air pump casing respectively. A needle valve 109 having a threaded stem 110 is mounted in the body member 103 and is operated by means of a control wheel 111, the needle valve being moved to and from the needle valve seat 106 to regulate flow through the fine bore 108 into the registering central passages 56 and 43 providing for oil flow to the interior of the air pump chamber 15 and oil wicks 47. A cap 112 encloses the control wheel 111 and suitable sealing gaskets 113 are provided to afford a seal between the body member 103 and the boss 104 and between the cap 112 and body member.

The air-oil pump, according to the invention, may conveniently be mounted on any standard mounting bracket used in conventional gun-type oil burner installations when it is to be used with such installations, and the intake side of the oil pumping section 13 can be coupled to the oil line 114 leading from a tank or other oil supply, such connection being conveniently effected through a fitting 115 which provides for the return of excess oil through the line 101, as shown in FIGURE 1. The air and oil control units 5 and 6 will, of course, be secured to the mounting face 41 of the air-oil pump unit to suit the direction of rotation which will be imparted to the pumping devices. The output from the air flow control unit 5 will be connected to the air line 7 as will the output of the oil flow control unit 6 be connected to the oil line 8. Then through the valves 59 and 59' and 77 and 77', the air and oil volume and pressure can be quickly and easily set to suit the particular requirements of the installation. It will be noted that for convenience in manufacture and use, all pressure regulating and volume control valves are interchangeable in their mountings.

While I have disclosed the preferred embodiments of my invention, it will be understood that variations in the details of construction and in the component parts employed may obviously be made by those skilled in the art without departing from the spirit of the invention or scope of the appended claims.

What I claim is:

1. A reversible air and oil pump device adapted to be driven in a first direction or a reverse direction comprising

ing: a fixed housing defining, an air pump chamber, and an oil pump chamber; a reversible rotary air pump device rotatably mounted in said air pump chamber, a reversible rotary oil pump device rotatably mounted in said oil pump chamber; a common drive means for said air and oil pump devices; said housing including, a mounting face, and further characterized in defining, a plurality of individual passage means constituting inlet and outlet passages to said oil pump chamber, and a plurality of individual passage means constituting inlet and outlet passages to said air pump chamber, said passages to said air pump chamber terminating in openings on said mounting face, said openings being substantially symmetrical and regularly disposed about an axis; a flow-control unit 5 associated with each of said pump outlets to receive the fluid delivered thereby, said units each including; an outlet passage formation communicable with their respective pump outlets and with an external installation, adjustable valve means for controlling volume flow through 10 said outlet passage, an air by-pass communicating said air outlet passage with the atmosphere and adjustable pressure delivery valve means controlling air flow therethrough, an oil by-pass communicating said oil outlet passage with an intake side of said oil pump and adjustable pressure delivery means controlling oil flow therethrough, said air flow control unit including an air intake passage formation, said air intake and air outlet passage formations having openings communicable with the respective openings of said housing, said air flow control unit further including a 20 mounting face, said air intake and outlet passage formations each having at least one opening cooperable with the respective inlet and outlet openings of said housing mounting face, said oil flow control unit comprising; an oil control block adapted to be mounted in face to face relationship with a face of said air control unit opposite to said mounting face; said oil control block having a well therein communicable with said oil outlet passage formation; and bleed passage means communicating said oil block well through said air block and said housing mounting face with 30 said air pump chamber, said bleed passage terminating in a bore of reduced diameter intermediate said inlet and outlet passage means to provide therebetween in cooperation with said air pump an oil seal, and means controlling oil feed through said bleed passage means.

2. A reversible air and oil pump device adapted to be driven in a first direction or a reverse direction comprising: a fixed housing defining, an air pump chamber, and an oil pump chamber, a reversible rotary air pump device rotatably mounted in said air pump chamber, a reversible rotary oil pump device rotatably mounted in said oil pump chamber; a common drive means for said air and oil pump devices; said housing including, a mounting face, and further characterized in defining, a plurality of individual passage means constituting inlet and outlet passages to said oil pump chamber, and a plurality of individual passage means constituting inlet and outlet passages to said air pump chamber, said passages to said air pump chamber terminating in openings on said mounting face, said openings being substantially symmetrical and regularly disposed about an axis; a flow-control unit 5 associated with each of said pump outlets to receive the fluid delivered thereby, said units each including; an outlet passage formation communicable with their respective pump outlets and with an external installation, adjustable valve means for controlling volume flow through said outlet passage, an air by-pass communicating said air outlet passage with the atmosphere and adjustable pressure delivery valve means controlling air flow therethrough, an oil by-pass communicating said oil outlet passage with an intake side of said oil pump and adjustable pressure delivery means controlling oil flow therethrough, said air flow control unit including an air intake passage formation, said air intake and air outlet passage formations having openings communicable with the respective openings of said housing, said air flow control unit further includ-

ing a mounting face, said air intake and outlet passage formations each having at least one opening cooperable with the respective inlet and outlet openings of said housing mounting face, said oil flow control unit comprising; an oil control block adapted to be mounted in face to face relationship with a face of said air control unit opposite to said mounting face; said oil control block having a well therein communicable with said oil outlet passage formation; and bleed passage means communicating said oil block well through said air block and said housing mounting face with said air pump chamber, said bleed passage terminating in a bore of reduced diameter intermediate said inlet and outlet passage means to provide therebetween in cooperation with said air pump an oil seal, means controlling oil feed through said bleed passage means; said air pump housing being provided with passage means running laterally of said bleed passage means, and means in communication with said latter passage means for feeding

5

10

15

oil to said air and oil pump driving means to seal said air chamber at opposite sides of said rotary air pump.
